UNITED STATES PATENT OFFICE

2,460,505

TOWEL RACK

William J. Jaboda, Put-in-Bay, Ohio

Application July 8, 1947, Serial No. 759,591

4 Claims. (Cl. 211—100)

1
This invention relates to supports, and more particularly to a towel-rack.

A main object of the invention is to provide a novel and improved towel rack of the folding-type which is very simple in construction, easy to install and neat in appearance.

A further object of the invention is to provide an improved towel rack which is inexpensive to manufacture, simple to manipulate and very sturdy in construction.

Further objects and advantages of the invention will become apparent from the following description and claims, and from the accompanying drawings, wherein:

Figure 1 is a top plan view of a towel rack constructed in accordance with the present invention.

Figure 2 is a front elevational view of the towel rack of Figure 1.

Figure 3 is an enlarged fragmentary cross-sectional detail view taken on line 3—3 of Figure 1.

Figure 4 is a view of a portion of the rack-arm structure of Figure 3 but showing said rack-arm structure in an inoperative position.

Figure 5 is a cross-sectional detail view taken on line 5—5 of Figure 3.

Figure 6 is a longitudinal cross-sectional view taken through the end portion of a rack arm employed in the towel rack of Figure 1.

Referring to the drawings, 11 designates a vertical plate member or support adapted to be secured to a kitchen wall or other suitable vertical surface. Plate member 11 is formed with a reverse bend 12 at its top portion, said reverse bend defining an inner vertical plate element 13, said plate element being arcuately downwardly bent at 14 and extending horizontally at 15. The end of horizontal portion 15 is bent to form an almost cylindrical depending trough 16 extending in a horizontal direction parallel to plate member 11. As shown in Figure 1, the shape of horizontal portion 15 is outwardly flaring, and the troughlike portion 16 is at the base of the trapezoid defined by said portion 15.

The troughlike portion 16 is formed with spaced slots 17, said slots being in outwardly flaring angular relationship, and seated in said troughlike portion and rotatably engaging the edges of the slots 17 therein are spherical ball members 18, said ball members being thereby retained against vertical or lateral movement in said trough portion. Each ball member 18 is formed with a bore 19 extending therethrough and slidably fitting said bore is a round rack arm 20. The diameter of rack arm 20 is just small enough to allow the

2
rack arm to pass freely between the walls of the slot 17 on the edges of which its associated ball member 18 is seated.

Secured to the ends of each rack arm, as by threaded studs 21, carried thereby are ball members 22, the threaded studs threadedly engaging inside threads formed in the ends of the rack arm. When the rack arms are in horizontal outwardly extending positions, the inner ball ends 22 thereof are received in the recess defined by the arcuately curved plate portion 14, the major portions of the rack arms extending outwardly beyond the pivot ball members 18 so that the weight of said major portions holds the rack arms in horizontal positions.

The rearward portions of the slots 17 are circularly enlarged, as shown at 23, so that by sliding the rack arms outwardly through the bores 19 in the ball members 18, and by then rotating said rack arms downwardly, the inner end balls 22 of the rack arms pass upwardly through the circularly enlarged slot portions 23 and allow the rack arms to be positioned vertically in inoperative depending positions with said inner end balls 22 engaging the ball members 18 and being received between an arcuate outer retaining lip 24 for the ball members 18 formed on the outer edge of the trough 16 and the inner bent ball retaining top edge 25 of said trough, as shown in Figure 4. The arms may be returned to horizontal positions by reversing the procedure above described.

The parts of the towel rack are preferably made of non-corrosive metal such as stainless steel, suitably plated brass, or the like, so that the sliding fit of the rack arms in the balls 18 will not be impaired by oxidation or corrosion of the parts. If desired, suitable durable non-metallic materials such as plastic materials may be employed for the towel rack components.

While a specific embodiment of a towel rack has been disclosed in the foregoing description, it will be understood that various modifications within the spirit of the invention may occur to those skilled in the art. Therefore, it is intended that no limitations be placed on the invention other than as defined by the scope of the appended claims.

What is claimed is:

1. A towel rack, comprising a support, a forwardly extending plate member carried by said support, the forward end portion of said plate member being formed with a depending channel, said plate member being formed with a plurality of slots extending through the lower portion of said channel, ball members rotatably supported

on the edge portions of the slots in said channel, and rack bars passing through said slots and slidably passing through openings in said ball members, said rack bars having enlarged inner end portions adapted to engage the bottom of the plate member in horizontal position, and to be supported on the ball members when the rack bars are in depending position.

2. A towel rack, comprising a support, a forwardly extending plate member carried by said support, the forward end portion of said plate member being formed with a depending channel, said plate member forward end portion being formed with a plurality of slots extending through the lower portion of said channel, said slots being in forwardly divergent angular relationship, a ball member rotatively supported on the edges of each slot in the channel, a rack bar slidably passing through an opening in each ball member and passing through the slot associated therewith, the inner end of the rack bar being enlarged beyond the width of the forward portion of the slot, and the rear portion of the slot being enlarged to allow said enlarged rack bar inner end to pass therethrough, the enlarged inner end portions of the rack bars adapted to engage the bottom of the plate member in horizontal position, and to be supported on the ball members when the rack bars are in depending position.

3. A towel rack, comprising a vertical support, a forwardly extending horizontal plate member carried by said support, the forward end portion of said plate member being formed with a depending approximately cylindrical channel, said forward end portion being formed with a plurality of slots extending through the lower portion of said channel, ball members rotatively supported on the edges of the slots in the channel, a rack bar slidably passing through an opening in each ball member and passing through the slot associated therewith, the end of each rack bar being enlarged beyond the width of the forward portion of the slot and the rear portion of the slot being enlarged to allow passage therethrough of the inner enlarged rack bar end, the enlarged

inner end portions of the rack bars adapted to engage the bottom of the plate member in horizontal position, and to be supported on the ball members when the rack bars are in depending position.

5. A towel rack, comprising a vertical support, a forwardly extending horizontal plate member carried by said support, said plate member being upwardly recessed adjacent said support, the forward end portion of said plate member being formed with a depending approximately cylindrical channel, said forward end portion being formed with a plurality of slots extending therethrough and through the lower portion of the channel, said slots being in forwardly divergent angular relationship, ball members rotatively supported on the slot edges in the channel, a rack bar slidably passing through an opening in each ball member and passing through the slotted channel walls adjacent the ball member, the ends of each rack bar carrying a ball enlargement exceeding in width the width of the forward portion of the slot, and the rear portion of the slot being enlarged to allow passage therethrough of the inner enlarged end portions of the rack bars, the lengths of each rack bar being more than twice the distance of the ball member from the vertical support, whereby each rack bar may be supported in horizontal position by its own weight with the enlargement engaging the recess in the plate member.
